Filed Mar. 13, 1961, Ser. No. 64,240

Term of patent 7 years

(Cl. D65—1)

FIG. 1 is a top plan view of a rocker pump showing my new design.

FIG. 2 is an elevational view as seen from the lower side of FIG. 1 with a portion thereof broken away for convenience of illustration.

FIG. 3 is an elevational view as seen from the right side of FIG. 1, also with a portion broken away for convenience of illustration.

The dominant features of the design reside in the portions shown in the drawing in full lines.

I claim:

The ornamental design for a rocker pump, substantially as shown and described.
